UNITED STATES PATENT OFFICE.

JOSEPH H. GLAUBER, OF CLEVELAND, OHIO.

STOP AND WASTE COCK.

SPECIFICATION forming part of Letters Patent No. 606,535, dated June 28, 1898.

Application filed November 9, 1897. Serial No. 657,960. (No model.)

To all whom it may concern:

Be it known that I, JOSEPH H. GLAUBER, a citizen of the United States, residing at Cleveland, in the county of Cuyahoga and State of Ohio, have invented certain new and useful Improvements in Stop and Waste Cocks; and I do declare that the following is a full, clear, and exact description of the invention, which will enable others skilled in the art to which it appertains to make and use the same.

My invention relates to improvements in stop and waste cocks; and the invention consists in a stop and waste cock in which there are a main valve to close the flow of the water through the cock and a waste-valve for controlling the waste-outlet, all substantially as shown and described and particularly pointed out in the claims.

Referring to the accompanying drawings, Figure 1 is a central sectional elevation of a stop and waste cock embodying my invention and showing the main valve closed and the waste-valve open. Fig. 2 is a cross-section of the cock at right angles to Fig. 1 and intersecting the outlet-passage from the waste-valve chamber, but which passage may be either on the opposite side of the cock in Fig. 1 or in the cut-away side at the front. Fig. 3 is a modification of the invention with a different form of main valve, as hereinafter described.

A represents the body or barrel of the cock, B the main valve, and C the seat of the main valve.

D is a threaded valve-controlling stem or spindle having a handle E to turn the valve to and from its seat, and F is a threaded plug in which the valve-spindle is engaged. Now in order that this mechanism may be utilized for stop and waste purposes I have formed the body or casing A of the cock with a waste well or chamber G, and this chamber is located at a point directly opposite the seat C of the main valve B, whether the cock be vertical or horizontal, and is packed and closed on its outside against leakage.

Two waste-water ducts or passages are connected with this well or chamber, the inlet duct or passage 3, Fig. 1, which communicates with the waste side of the cock to draw or waste the water out of the pipe when the main valve is closed, and the outlet duct

or passage 4, Fig. 2, leading from the top or inner side of said well or chamber out through the discharge-nipple 5.

It will be noticed that the chamber G is shown here directly below valve B. This is made possible by arranging said valve above the seat and diaphragm C, so as to open upward. Then beneath said diaphragm C, below the water space thereunder, is a diaphragm 6, forming the top or inner wall of the waste-chamber. From this wall there extends a tube 7 upward to valve B, and downward through said tube is a stem or projection 8 to bear on the waste-valve, as hereinafter described. A waste-valve K occupies the chamber G and closes upward against the outlet-passage 4, while the inlet-passage 3 is always behind said valve.

The stem 8 is designed to so closely occupy the neck 7 that it will close it against water passage or pressure from above.

The projection or point 8 on valve B bears on the waste-valve K when valve B is closed, and valve K is supported by a spiral spring 9 resting on the bottom of chamber G and pressing the valve to its seat. A spring of such strength as will simply hold said valve K to its seat will be sufficient, because I do not in fact rely on the spring to hold the valve to its seat, but on the pressure of the water, and the heavier this pressure the closer the valve is held. It will be noticed that the inlet-passage 3 discharges into chamber G beneath valve K, even when said valve is open, and the stem or projection 8 is of such length that said valve will be opened relatively about as shown when the main valve is closed. Hence as soon as the stem 8 is withdrawn by opening the main valve the waste-valve is pressed to its seat not only by the spring 9, but by the back pressure of the water from below. I may of course use a spring of sufficient strength to hold the valve K firmly to its seat; but my construction and arrangement of parts have the advantage of being able to utilize the water-pressure alone for this purpose or as a reinforcement of the spring.

In Fig. 3 I show a modification of the invention, in which I employ a straightway valve L in the casing M; but in all other respects the invention is the same substantially

as in the foregoing views, and the same parts are employed to effect the waste.

Among the advantages of my invention over waste-cocks heretofore in use I may mention the following:

First. The old style of cocks, when used in a horizontal position, would not allow the waste water which was in the pipes to run off on account of the waste-hole being up so high 10 above the seat that it was above the level of the pipe to be drained. In my cock the waste is below the level of the pipe, and it will waste whether set horizontally or vertically.

Second. All the ordinary cocks waste continually from the time of opening the valve until the stem is turned entirely up, requiring it to be screwed around several times before closing can occur. Therefore they cannot be used partly open or partly closed, and 15 the slightest turn of the stem makes them leak out of the waste.

My waste is not disturbed until the main valve is practically closed, and the waste closes instantly when the main valve is 25 opened. Furthermore, my cock wastes from beneath the seat and at the same time has the pressure on the lower side and not against any of the working parts when closed. Again, my waste-valve can be removed for repairs 30 without disconnecting or disturbing the main valve—a very great advantage.

The terms "top" and "bottom," "beneath" and "above," or the like when applied to the main valve in its relation to the waste-chamber or to said chamber or its valve in 35 relation to the main valve are understood to apply whether the cock be set in a horizontal or a vertical position, these terms serving especially to simplify description.

40 By closing the main valve from above its seat the said valve is brought onto the exhaust side of the seat, and this enables me to place the waste-chamber and mechanism directly beneath said seat and beneath the 45 water-pressure and yet not have the water-pressure directly open to the waste mechanism. When the main valve is open, however, the pressure comes through and into the waste-chamber, as already described.

50 It will be observed that by the foregoing construction there are two diaphragms C and 6. in parallel planes and between which there is a constant presence of the pressure fluid. This brings the waste-chamber directly beneath the pressure fluid and is rendered possible by the tubular neck 7, extending up 55 from diaphragm 6 and affording a way to communicate mechanically from main valve B to the said exhaust-chamber through the 60 water-pressure over said chamber.

What I claim is—

1. In stop and waste cocks, the body of the cock constructed with two parallel diaphragms having a space between them constantly open to water-pressure, and a tubular projection from one of said diaphragms into

said water-space and the main-valve seat on the other diaphragm, substantially as described.

2. The body of the cock having two diaphragms and a waste-chamber beneath the same, one of said diaphragms having a passage for the water and the other a projection into the space between said diaphragms and open through its center into the said waste-chamber, substantially as described. 75

3. The body of the cock provided with two diaphragms, one of said diaphragms having a seat for the main valve and a waste-chamber covered by the other diaphragm in which is 80 a central passage opening into said waste-chamber, in combination with the waste-valve, the main valve and a close-fitting projection extending through said central passage and engaging said waste-valve, substantially as described. 85

4. The body of the cock having two diaphragms with an open water-pressure space between them, and a waste-chamber beneath the lower of said diaphragms having its waste 90 at the top, in combination with a main valve seated on the upper diaphragm and an exhaust-valve seated on the lower diaphragm to close said outlet, and a projection from the main valve engaging the waste-valve, substantially as described.

5. The body of the cock having the main-valve diaphragm therein, and a waste-chamber having a diaphragm closing the top thereof; the main valve and the waste-valve arranged to seat toward each other on said diaphragms respectively, and a waste-outlet between said valves controlled by the waste-valve, and a projection from the main valve 95 engaging the waste-valve to open the same, substantially as described. 100

6. A stop and waste cock having one diaphragm dividing said cock into water-pressure and exhaust sides and provided with a valve-seat and a valve opening to the exhaust side from said seat, a waste-valve chamber opposite said seat and a separate diaphragm over the same separating said chamber from the water-pressure side of the cock, a valve in said chamber and means to open said valve 115 connected with the main valve, substantially as described. 110

7. The body of the cock provided with a main-valve diaphragm across its center and a valve seated on the exhaust side of said diaphragm, a waste-chamber beneath said main valve and a diaphragm closing it from the water-pressure over the same, a waste-valve in said waste-chamber and means extending to the main-valve stem to open the waste-valve, substantially as described. 120 125

Witness my hand to the foregoing specification this 4th day of November, 1897.

JOSEPH H. GLAUBER.
